UNITED STATES PATENT OFFICE.

WILLIAM J. SCHULTZ, OF DETROIT, MICHIGAN, ASSIGNOR OF ONE-HALF
TO CHARLES L. VIEMAN AND WILLIAM H. TURNER, OF DETROIT,
MICHIGAN.

AIR-COMPRESSOR.

No. 806,924.

Specification of Letters Patent.

Patented Dec. 12, 1905.

Application filed June 11, 1904. Serial No. 212,076.

To all whom it may concern:

Be it known that I, WILLIAM J. SCHULTZ, a citizen of the United States, residing at Detroit, county of Wayne, State of Michigan, have invented a certain new and useful Improvement in Air-Compressors; and I declare the following to be a full, clear, and exact description of the invention, such as will enable others skilled in the art to which it pertains to make and use the same, reference being had to the accompanying drawings, which form a part of this specification.

My invention relates to an improvement in air-compressors shown in the accompanying drawings and more particularly set forth in the following specification and claims.

In the drawings, Figure 1 is a plan view of my invention. Fig. 2 is an inverted plan view of the same. Fig. 3 is a longitudinal section through the pump-cylinder and the valve controlling the operation of the pump on line 3 3 of Fig. 2. Fig. 4 is a longitudinal section through the opposite pump-cylinder on line 4 4 of Fig. 1, showing an auxiliary cylinder in which is contained a piston governing the operation of the valve shown in Fig. 3. Fig. 5 is a longitudinal section of a detail on line 5 5 of Fig. 1, showing the means employed to throw the driving-pulley of the pump into or out of engagement with the driving-pulley operating the same. Fig. 6 is a cross-sectional view through the cylinders and supporting parts on line 6 6 of Fig. 2. Fig. 7 is a side elevation showing the driving-pulleys in frictional contact and in dotted lines the position of the driving-pulley when the pump is at rest. Fig. 8 is a detail showing the antifriction-rollers over which the sliding carriage moves.

One of the objects of my invention is to construct an air-compressor that will be operated by a suitable driving-pulley brought into frictional engagement with an independent driving-pulley operated by any external means, the construction being such, however, that when the predetermined pressure in the storage tank or tanks has been secured the driving-pulley operating the pumps will be automatically thrown out of frictional engagement with the pulley employed to drive the pump by the air-pressure itself. When the pressure in the storage-tank falls below its fixed or predetermined pressure, the pulley controlling the action of the pumps will

be forced again into frictional contact with the driving mechanism. It will thus be seen by further reference to the specification that the operation of the pumps is governed entirely by the condition of the pressure in the storage-tanks, the pumps being idle when the predetermined pressure is intact, or vice versa.

Referring to the letters of reference shown in the drawings, A is the frame of the pump.

B and B' are the pump-cylinders.

b and b' are the pistons connected by the pitmen b² and b³ with the disks C and C', supported on the shaft D, mounted on suitable bearings on the sliding carriage E.

b⁴ and b⁵ are check-valves governing the inlet and delivery ports of the pump-cylinders.

A' is a frame housed within the recesses formed in the bed plate or frame A and projecting into like recesses formed in the frame of the sliding carriage E.

A² represents friction-rollers journaled in the frame A', over which the sliding carriage E travels.

e' e' are pins secured to the frame A and projecting into the slotted way formed in the sliding carriage E to act as guides when said frame reciprocates. The raised portion a', formed in the fixed frame A, also serves to guide the sliding carriage E by projecting into a slotted way at the other end of the traveling carriage.

D' is a driving-pulley mounted on the shaft D.

F is a driving-shaft, and F' is a pulley mounted thereon, designed to drive the pulley D' when the latter is brought in frictional contact with its rotating surface.

E' is a spring, one end of which is engaged with the lug E², secured to the raised portion a' of the fixed frame A, the other end of the spring having a bearing on the projecting pin E³, secured to the traveling carriage E, the action of the spring serving to force the pulley D' into frictional engagement with the pulley F'.

G represents pipes (having a flexible section g) leading from the pump-cylinders B to a slide-valve chest H.

G' is a pipe leading from the chest to an auxiliary cylinder I.

G² is a pipe leading to a storage-tank (not shown) from a T in the pipe G' between the valve-chest and the auxiliary cylinder I. I'

is a piston housed within said cylinder, the rod of which projects through an adjustable sleeve i , mounted in the frame A, which serves as a bearing for the spring I^2 , coiled around 5 the rod and bearing against the piston I' . By adjusting the sleeve i the tension of the spring may be increased or diminished, as required.

i^2 is an adjustable collar secured to the piston-rod, and which is engaged by the rocking 10 arm J, pivoted to the frame A.

H' is a slide-valve housed within the valve-chest H, its operating-rod projecting through the chest and having an adjustable collar h secured thereto, which is engaged by the other 15 end of the rocking arm J, the rocking arm J being provided with fingers straddling the rod of the piston I' and engaging the collar i^2 , while similar fingers at the opposite end engage the collar on the rod of the slide-valve 20 H, as before explained.

J' is a finger projecting from the rocking arm on a radial line from its pivot. J^2 is a spring bearing on the end of said projecting finger J' and engaging a stud pivoted to the 25 frame A, the object being to hold the arm against accidental displacement when thrown in either direction by the movement of the piston I' .

K and K' are pipes leading from ports in 30 the valve-chest H to two oppositely-disposed air-chambers L and L', in which are secured leather or other suitable diaphragms l and l' .

K² is an exhaust-port in the valve-chest H.

M is an arm secured to the sliding carriage 35 and traveling in a slotted way formed in the frame A. The arm has a double convex portion M' bearing on the diaphragms l and l' .

I will now proceed to explain the operation 40 of my invention. The pump-frame being mounted adjacent to the independent driving-pulley, the action of the spring E' will force the carriage supporting the driving-pulley of the pump B into frictional contact with the independent driving-pulley. The pumps are 45 thus set in motion and air delivered from the pump-cylinders by way of the slide-valve chest H, through the pipes G' and G², to a storage-tank (not shown) until a predetermined pressure has been secured, controlled 50 by the action of the spring I², bearing against the piston I', the tension of the spring I² being regulated by the adjustment of the sleeve i . Now any further delivery and compres-

sion of air in the storage-tank will force the 55 piston I' against the action of the spring I² and the projecting piston-rod will, through the action of the adjustable collar i^2 , secured thereto, operate the rocking lever J, causing the fingers on the end of the rocking lever to 60 engage the adjustable collar on the stem of the slide-valve, thrusting the valve to the limit of its movement. By this action air will pass through the pipe K from the valve-chest H into the diaphragm-chamber L, distending 65 its diaphragm and forcing the arm M, se-

cured to the traveling carriage, to the limit of its movement, thereby throwing the driving-pulley D' of the pump out of frictional contact with the independent driving-pulley E'. When the air in the storage-tank falls 70 below its predetermined compression, the action of the spring I², bearing on the piston I', will cause the piston to return to the position occupied before compression of air in the storage-tank. In so doing the adjustable collar 75 on the piston-rod will engage the rocking lever J and cause it to tilt in the opposite direction, permitting the air in the valve-chest H to pass out through the pipe K' into the opposite diaphragm-chamber L', distending its 80 diaphragm and forcing the projecting arm M, secured to the sliding carriage, forward, thereby pushing the carriage to the limit of its movement in the opposite direction and causing the pulley D', controlling the operation 85 of the pump, to come in frictional driving contact with the independent driving-pulley F'. As the slide-valve changes its position it will be apparent that the air in the diaphragm-chamber L will exhaust through the port K², as will also the air from the diaphragm-chamber L' when the slide-valve is moved in the 90 opposite direction. It will be seen that the spring E' is employed merely to secure the initial operation of the pump. After the 95 storage-tank is supplied with air the action of the sliding carriage is practically independent of the spring, which could then be dispensed with, as the condition of the pressure in the storage-tank will automatically 100 control the operation of the pump. It will now be readily seen that when the air in the tank drops below its predetermined compression the action of the spring I² on the auxiliary piston controlling the movement of the 105 slide-valve will automatically shift the slide-valve so as to deliver air from the storage-tank into the diaphragm-chamber L', and by means of the parts operating therewith the sliding carriage upon which the pump-driving 110 pulley is mounted will force the pump-driving pulley into frictional driving contact with the independent driving-pulley until the pressure in the storage-tank has reached its predetermined pressure, when the pumps will 115 be thrown automatically out of operation.

Having thus described my invention, what I claim is—

1. In an apparatus of the class described, a reciprocating carriage, compression-pumps mounted thereon, a frictional driving-pulley mounted on said carriage and geared to operate the pumps, a main driving-pulley to operate said pump-pulley, means operated by the air under compression to shift the pump-driving pulley into or out of frictional driving contact with the main driving-pulley as determined by the air-pressure itself, substantially as described. 120

2. In an apparatus of the class described, a 125

sliding carriage, a driving-pulley to operate the compression-pumps, an independent driving-pulley to operate said pump-driving pulley by frictional contact, a fixed frame, air-chambers provided with elastic diaphragms supported therein, an arm secured to the sliding carriage and lying adjacent to the diaphragms of the air-chambers, means for delivering the air to and exhausting it from the air-chambers alternately, whereby the alternate distention of the diaphragms bearing against the arm of the sliding carriage will cause it to reciprocate thereby bringing the frictional driving-pulleys into or forcing them out of driving relation, substantially as described.

3. In an apparatus of the class described, a sliding carriage carrying a friction driving-pulley to operate compression-pumps, two oppositely-disposed diaphragmed air-chambers, an arm secured to said sliding carriage and projecting between the air-chambers adjacent to the diaphragms, and means for admitting air to and exhausting from said air-chambers alternately whereby the sliding carriage is given a reciprocating movement in order that the driving-pulleys may be brought into frictional driving contact or released therefrom, substantially as described.

30 4. In an apparatus of the class described, a sliding carriage carrying a frictional driving-pulley to operate compression-pumps and having channels to receive a frame, a fixed frame provided with similar channels, a frame interposed between the fixed frame and sliding carriage and housed within the channels formed in the carriage and fixed frame, said intermediate frame provided with antifriction-rollers upon which the carriage travels, substantially as described.

40 5. In an apparatus of the class described, a sliding carriage, a driving-pulley to operate the compression-pumps, an independent driving-pulley to operate said pump-driving pulley by frictional contact, air-chambers provided

with elastic diaphragms, an arm secured to the sliding carriage and projecting between the oppositely-disposed air-chambers adjacent to their elastic diaphragms, an auxiliary cylinder fitted with a piston having a projecting rod 50 engaging a rocking lever, the lever, a valve-chest, pipe connections from the compression-pumps to the valve-chest and from the valve-chest to the auxiliary cylinder, to the storage-tank and to the diaphragmed air-chambers, and a sliding valve housed within the valve-chest under the control of said rocking lever to govern by its movement the admission and release of air to each of the air-chambers alternately, substantially as described.

55 6. In an apparatus of the class described, a sliding carriage, compression-pumps suitably mounted, a driving-pulley to operate the compression-pumps mounted on the sliding carriage, an independent driving-pulley designed to operate the driving-pulley mounted on the sliding carriage when the latter is brought into frictional contact therewith, means controlled by a rocking lever for reciprocating 65 said sliding carriage, the rocking lever, an auxiliary cylinder fitted with a piston having a projecting rod connected with said rocking lever, a spring having a bearing against one side of said piston, means for increasing the 70 tension of said spring, pipe connections between said auxiliary cylinder and the source of air compression, whereby when said compression has reached a predetermined pressure the piston is forced against the tension 75 of the spring to operate the rocking lever and to throw the frictional driving-pulley out of driving contact with the power controlling the same, substantially as described.

80 In testimony whereof I sign this specification in the presence of two witnesses.

WILLIAM J. SCHULTZ.
